DESIGN FOR A HORN

Gaetano Carbonaro, Brooklyn, N. Y., assignor to
E. A. Laboratories, Inc., Brooklyn, N. Y., a corporation of New York

Application June 28, 1939, Serial No. 85,740

Term of patent 14 years

To all whom it may concern:

Be it known that I, Gaetano Carbonaro, a citizen of U. S. A., residing at Brooklyn, in the county of Kings and State of New York, have invented a new, original, and ornamental Design for a Horn, of which the following is a specification, reference being had to the accompanying drawings, forming a part thereof, wherein:

Fig. 1 is a side elevation of a horn showing my new design;

Fig. 2 is a front view thereof; and
Fig. 3 is a bottom plan view thereof.

The dominant feature of the design resides in the portion shown by solid lines.

I claim:

The ornamental design for a horn, as shown and described.

GAETANO CARBONARO.
